UNITED STATES PATENT OFFICE

CHRISTOPHER PETERSON, OF LOS ANGELES, CALIFORNIA

SUNKEN-SUBMARINE INDICATOR

Application filed February 13, 1929. Serial No. 339,565.

My invention is a sunken submarine indicator.

An object of my invention is an indicator which may be released by a sunken submarine and when a buoy is floated to the surface of the water gives a signal. In addition the buoy has a connection for telephone communication and the mooring cable of the buoy may be utilized to lower a cable ring, this ring becoming engaged with a hook on the submarine so that by utilizing a sufficient number of hooks the submarine may be salvaged.

A further object of my invention in connection with the signal is mounting a plurality of skyrockets or the like in the top of the buoy, these being arranged to be fired electrically from the sunken submarine; the rockets thereby giving signals to vessels and indicating the approximate position of the sunken submarine. In this connection a further object of my invention is in locating the skyrockets in water tight compartments, the top of such compartments being frangible and broken by the discharge of a rocket.

Another object of my invention in connection with the buoy is the manner of releasing the buoy from a container in the submarine, this being done by the container filling with water and the buoy in floating unlatching closure hatches in the deck of the submarine. When the buoy rises to the surface a salvage vessel may get into communication with the submarine by a telephone connection and on unhitching the mooring cable from the buoy an air hose may be pulled down into the submarine, or from the submarine up. Therefore a still further object of my invention is in the constructional mechanism of the submarine by which the hose may be pulled into the interior.

In salvaging a submarine a further object of my invention is in having a substantial hook located in the buoy compartment, this hook being arranged to engage with a ring which may be slid downwardly on the mooring cable so that it will pass underneath the hook and this hook may then function to allow lifting or salvaging of the submarine. For this use it is desirable that there be a plurality of releasable buoys with a hook in

the buoy compartment. As a modification I may employ a buoy with a hose connected thereto, this buoy being floatable to the surface and having an air intake, this being arranged with a frangible closure. This closure may be ruptured by the crew of the submarine pulling on the wire and thereby allow inflow of air through the hose.

My invention is illustrated in the accompanying drawings, in which:

Figure 1 is a plan of a hatch partly broken away, over the buoy compartment;

Fig. 2 is a vertical section on the line 2—2 of Fig. 1 in the direction of the arrows;

Fig. 3 is a plan of the buoy, omitting the compartment;

Fig. 4 is a vertical section of the lower part of the buoy compartment, showing the manner of passing a hose into the submarine or out;

Fig. 5 is a diagrammatic elevation and vertical section showing the floating buoy connected to the sunken submarine;

Fig. 6 is a diagrammatic elevation and part vertical section showing a step in the salvaging of the submarine by lowering the lifting ring;

Fig. 7 is a vertical section through a modified form of buoy having an air hose connected thereto;

Fig. 8 is a detail vertical section through the intake end of the hose of Fig. 7, illustrating the frangible inlet cover;

Fig. 9 is a detail showing the method of securing a mooring ring or hook to the submarine by pulling downwardly on the buoy cable when detached from the buoy.

Referring first to the construction of Figs. 1 through 4, the buoy compartment designated generally by the numeral 11 is illustrated as having cylindrical sides 12 and a floor 13. The sides terminate at the deck 14 of the submarine. A hatch 15 has two leaves 16 and 17 mounted on spring hinges 18 on the deck of the submarine, these leaves overlap and the overlapping leaf has a depending stud 19 with a bell crank latch 20 connected thereto by the pin 21. The latch has a short hook arm 22 engaging underneath a detent 23 on the cylindrical wall 12.

The long arm 24 of the bell crank has a bent-down end 25.

The hatch is provided with openings 26 having frangible covers 27 which will break by the water pressure when the submarine is submerged to a substantially predetermined depth, such depth being greater than that to which the vessel would normally dive. The frangible material is protected by a grating 28. This allows flow of water into the buoy compartment. In order to flow water therein at lesser depth a pipe 29 having a valve 30 leads from the deck into the buoy compartment and may be controlled from inside the submarine. The air in the buoy compartment is allowed to escape by the pipe 31 having a control valve 32, this air preferably escaping into the submarine.

The buoy designated generally by the numeral 33 is more or less of a spherical structure and when in the compartment may be supported by the brackets 34 secured to the wall 12 of the buoy compartment. The buoy is provided with a closure cap 35 preferably riveted thereto having a central hand hole closure plug 36. This has a raised boss 37 which engages the downturned ends 25 of the long arms 24 of the bell crank latches 20. When water fills the buoy compartment it floats upwardly pressing on the long arms 24 and disconnecting the hook end 20 of the latch from the detent 23. This allows the leaves 16 and 17 of the hatch to turn outwardly under the influence of the spring of 35 the hinges and also by the force of the buoy in rising upwardly.

The buoy carries a mooring cable 38 detachably connected to its bottom, this cable being coiled as indicated at 39 on the floor of 40 the buoy compartment around the hub 40. The cable passes a water tight closure designated generally by the numeral 41. This closure is made by having a funnel-shaped structure 42 secured to the floor in the center 45 of the hub. The neck of this funnel is centered at an opening 43 in the floor. An open frame 44 is secured to the underside of the floor and in this a flexible rubber sleeve 45 is located; this sleeve being secured to the underside of the floor and to the bottom of the frame. The lower end of the sleeve 45 has flanges 46 engaged by the clamps 47 which will allow slight squeezing of this sleeve.

A split clamp ring 48 is fitted on the outside of the rubber sleeve and has tapered threads engaged by the nut 49. A removable bushing 50 which may be split if desired, is fitted around the mooring cable and inside of the rubber sleeve 45, this sleeve being clamped 60 tight to make a water-tight fit. The lower portion 51 of the mooring cable is coiled on a reel 52 mounted in a bracket 53 and operated by a crank 54 or other suitable means. (Note Figs. 2 and 4.)

65 When the buoy is floated to the surface and

been picked up by a salvage vessel, the mooring cable may be detached from the buoy and the upper end connected to a threaded plug 55 in a hose coupling 56 on the end of the flexible hose 57. The crew of the submarine may then reel in the mooring cable and in so doing pull down the air hose 57. This hose is guided by the funnel 42 and passing into the rubber sleeve 45. The bushing 50 is shoved out of place by the connection of the mooring cable to the plug 55 and at the same time the lower end of the hose enters the sleeve 45. The nut 49 is adjusted so as to squeeze the sleeve with the desired pressure.

A soft rubber washer 58 on the hose fits in the funnel 42 and prevents water passing downwardly on the outside of the hose. The hose should be well greased to allow free slipping through the rubber sleeve 45 and when the hose has been drawn into the submarine it may be connected by various hose or other pipe connections to the different compartments of the submarine and used to convey air either to sustain the life of the crew or blow out the water from flooded compartments. If desired, the salvage vessel may draw the hose upwardly from the submarine.

A separate electrical cable 63 is illustrated as being connected to the buoy passing through a plug 64. This is coiled as indicated at 65 in the floor of the buoy compartment, the coils being parallel to those of the mooring cable and this electric cable leads downwardly through a metal tube 66 constructed through the floor of the buoy compartment there being a packing gland with suitable packing 67 around the electric cable. This packing is sufficiently tight so cable may be let out or drawn in on the reel without admitting water. These constructions allow the mooring cable and also the telephone cable to be let out when the buoy rises to the surface and to be drawn inwardly if desired.

The indicator or signalling device is comprised of a series of skyrockets 68. Each of these rockets is mounted in a compartment 69 formed by a metal basket structure designated generally by the numeral 70 and depending from the closure cap 35. In the construction illustrated there are six of these rockets in the rocket compartment. Each of these compartments have a frangible cover 71 made of a suitable water-proof fabric or equivalent device which may be severed on the discharge of the rocket. The rockets are discharged by electrical means. The wires 72 in the electric cable lead to terminals 73 on the base of the rocket holding basket and in each of the rocket compartments there is an insulating plate 74 with contacts 75 which engage electric spark gap contacts 76 on the base of the rockets. Therefore when the buoy is floated to the surface the crew in the submarine may establish a circuit through 75

any one of the leads to the individual rockets; this giving an electric connection to the base of each rocket and in the rockets there is a 5 sparking device which ignites the powder; the discharge of the rockets breaking the frangible cover 71.

An electric light 77 is mounted on a holder 78 depending from the hand hole plug 36. This lamp has electric leads 79 connected from the electric conductor to the submarine. 10 By this means the light may be illuminated and shines outwardly through ports 80 having suitable glass covers, this being protected by grids. This means gives an illumination 15 of the buoy. The holder 78 is supported in a tube 82 depending from the hand hold opening and when the plug is removed the crew of the salvage vessel may move the telephone transmitter and receiver 83 and communicate by telephone with the crew of the 20 submarine.

The arrangement for salvaging the submarine is by means of the hook 84. This hook has a base illustrated as attached to the 25 side wall 12 of the buoy compartment as illustrated at 85. The hook has a perforation 86 therethrough through which extends the mooring cable 38. In Fig. 6 there is indicated a salvage vessel 87 with the mooring cable drawn up through a hawse-hole 88. The vessel is illustrated as lowering a heavy 30 ring 89 secured to a lifting cable or chain 90. This ring is guided by the mooring cable and slips over the lower end 91 of the hook 84. 35 The ring slips upwardly until it passes underneath the outwardly spring pressed latch finger 92 which is mounted on a pivot pin 93. When the ring is in firm engagement with the hook 84 an upward pull may be exerted 40 by the salvage vessel in the endeavor to raise the submarine. It is intended that the submarine will be equipped with a number of buoys with a sufficient number of hooks so that the salvage vessel may attach sufficient 45 lifting cable or chains to raise the submarine to the surface.

In Figs. 7 and 8 I illustrate a construction by which the buoy may carry an air hose and this hose may be opened from the submarine. 50 In this construction the buoy 94 may be of any suitable construction and is illustrated as having a deck surface 95 with an air intake hood 96 mounted thereon. This hood has a dome 97 with side walls 98 having openings 99 therein. The side walls are attached 55 to a flange ring 100 which fits in an opening in the deck 95. A tube 101 extends upwardly inside of the flange ring and has an outwardly and downwardly flared top or flange 102. 60 A ring-like plug 103 is mounted inside of the tube 101 and through this there is a tube 104 which has a pipe 105 fitted therein. This pipe passes downwardly through an opening in a ballast weight 106 in the base of the 65 buoy and passes through a compressible pack-

ing held by a packing gland 107 and is connected to a hose 107. This hose is intended to be coiled in the buoy compartment and to lead into the submarine so that on floatation of the buoy the hose will be pulled upwardly. 70 The tube 104 is provided with a frangible top closure 108 formed preferably of a suitable water proof fabric clamped between a ring 109 and a flange 110 of the pipe 104. A strong fine wire 111 such as piano wire extends 75 downwardly through the hose and is connected to the frangible cover 108.

This wire leads into the submarine so that on pulling on the wire by the crew the frangible top 108 may be broken and thus allow 80 intake of air. The dome 97, the openings 99 and the tube 101 of the downwardly curved flange 102 prevent entrance of water while allowing a free inflow of air. It is to be understood that the air will be drawn in the 85 submarine preferably by means of a pump.

In Fig. 9 I illustrate a manner of connecting a lifting or mooring ring or hook to the hook 84 in which case the buoy is detached from the cable 38 by a salvage vessel 90 87. A ring 112 is attached to the cable 38 and also a mooring or lifting cable 113 is attached to the ring. The cable 38 is then drawn downwardly into the submarine and the ring 112 is brought into engagement with the 95 hook 84. If on the first attempt the ring does not engage the hook, the mooring cable 113 may be drawn upwardly slightly and then the cable 38 may be pulled down into the submarine. The purpose of connecting 100 the lifting or mooring cable 113 is on account of the cable 38 connected to the buoy not being sufficiently strong for mooring a salvage vessel or for use in lifting. By this means a salvage vessel may be quickly moored to a 105 submarine when the same has been sunk and avoids the delay of having to send down divers or grapple for the submarine from a salvage vessel.

Small port holes 114 having heavy glass 110 therein are provided in the wall 12 of the buoy compartment. These are preferably placed diametrically opposite and by projecting a light through one of the port holes observers on the other side can ascertain if the 115 mooring ring or hook properly engages the lifting hook 84 and by means of the telephone they can communicate with the salvage vessel advising whether to lift or to lower the hook or ring or what direction of movement to 120 give this. Rubber buffers 115 are provided on the interior of the buoy compartment, preventing bumping of the buoy against the sides of the compartment.

Various changes may be made in the principles of my invention without departing from the spirit thereof as set forth in the description, drawings and claims.

I claim:

1. In a device as described, a submarine 130

having a floatable buoy connected thereto, a cable connection from the buoy to the submarine, a series of rockets or flares mounted in the buoy, a frangible cover covering the top of each of the rockets or flares, and an electrical connection from the submarine to ignite the rockets or flares.

2. In a device as described, a submarine having a structure with a flexible resilient sleeve connecting from the interior to the exterior, a hose guide on the exterior, a hose having a rubber washer slidable on its periphery and engaging the said guide, means to pull the hose inwardly through the sleeve, and means to press the sleeve against the outside of the hose.

3. In a device as described, a submarine having a structure with a resilient compressible sleeve extending from its interior to the exterior, a cable having a bushing fitting in the said sleeve and extending outwardly from the submarine, means to engage the cable at the end of a hose, means to draw the cable into the submarine, the bushing becoming displaced, and means to press the sleeve against the exterior of the hose.

4. In a device as described, as claimed in claim 2, the submarine having a flared structure on its exterior with an opening in alignment with the sleeve and the hose having a resilient washer slidable on its exterior and engaging the said flared structure.

5. In a device as described, a submarine having a structure with a resilient compressible sleeve connecting the interior and exterior, a split clamp on the sleeve, means to compress said clamp, a bushing in the sleeve, a cable extending outwardly through the bushing, a floatable buoy detachably connected to the cable and a hose, means to connect the hose to the cable, and means to draw the cable and the hose through the said sleeve into the interior of the submarine.

6. In a device as described, a floatable buoy having a top structure with a plurality of compartments for flares or rockets, each compartment having a frangible covering, a rocket or flare in each compartment, and electrical means to ignite the rockets or flares.

50 7. In a device as described, a floatable buoy having a top with a basket structure depending therefrom in the interior of the buoy, said basket structure having a plurality of compartments, each having a frangible top, a rocket or flare in each compartment, an electrical connection to each compartment and from each compartment to each flare for the igniting of any one of the flares, a hand hole in the top structure having a removable plug and means in the interior of the buoy having an electrical connection whereby electric communication may be had with a submarine or the like.

60 8. In a device as described, a submarine vessel having a compartment, a floatable

buoy supported therein, a hatch having a plurality of leaves, a latch pivotally connected to the hatch and having a latch hook engaging a detent on the submarine, the latch having means engaging the buoy, means to flow water into the compartment whereby the floating of the buoy releases the latch, and means operable to open the leaves of the hatch after unlatching, the means to flow water into the compartment comprising openings through the hatch having a frangible covering therefor, said covering being adapted to break under a predetermined water pressure.

70 In testimony whereof I have signed my name to this specification.

80 CHRISTOPHER PETERSON.
